UNITED STATES PATENT OFFICE

1,967,560

PARCEL CARRIER

Axel Theodore Oberg, Eugene, Oreg.

Application November 23, 1933, Serial No. 699,437

1 Claim. (Cl. 224—57)

This invention relates to a parcel carrier, the general object of the invention being to provide a handle part and a hook-shaped part of double construction pivotally connected with the handle part and adapted to be pushed into a slot in the handle part when not in use, whereby the device can be used for carrying packages of various kinds and can be placed in the pocket or a purse when not in use.

10 This invention also consists in certain other features of construction and in the combination and arrangement of the several parts, to be herein-after fully described, illustrated in the accompanying drawing and specifically pointed out in 15 the appended claim.

In describing the invention in detail, reference will be had to the accompanying drawing wherein like characters denote like or corresponding parts throughout the several views, and in 20 which:—

Figure 1 is an elevation of the device in open position.

Figure 2 is a bottom plan view showing the hook member located in the slot in the handle 25 member.

Figure 3 is a transverse sectional view through Figure 1.

In this drawing, the numeral 1 indicates the handle part of the device which is of such a shape 30 as to readily fit the hand of the user and this handle part is provided with a slot or groove 2 which opens out through the under side thereof and extends from a point adjacent one end of the handle part to a point slightly beyond the middle 35 of the handle part. A pin 3 passes through the middle part of the handle member and through a portion of the slot or groove and receives the eye 4 formed in the carrying member 5. This carrying member 5 is formed of a length of spring 40 wire bent upon itself to form the eye 4 from which extends the shanks 6, one of these shanks terminating in a long curved hook 7, while the other terminates in an inclined part 8, the extremities of these parts 7 and 8 being rolled, as shown at 45 9, and they abut each other, as shown. The shanks 6 are flattened to provide the thin portions 10 so that these parts can be readily bent to space the rounded or rolled portions 9 apart to permit a string or the like to pass between 50 them. After the pressure is removed, the parts will spring back to contacting relation.

Thus it will be seen that when the device is not in use, the carrying part 5 can be pushed into the slot or groove 2 and then the device can be placed 55 in a pocket or in a purse or the like and it will

occupy but little room. When the device is to be put into use, the carrying part 5 is pulled out of the slot and into the position it occupies in Figures 1 and 3, so that a string or the like which passes around a package or parcel can be placed 60 in the hook 7, which will permit the parcel or package to be readily carried by one hand of the user grasping the handle part 1. The string or other part of a parcel or the like can be readily slipped between the ends 9 when the parts are 65 sprung sidewise and the shape of the parts prevents the parcel being accidentally dislodged from the hook. As will be seen, there are no sharp points or projections to damage the hand or clothing when in use or the pocket or purse when 70 collapsed.

This device can be used as a carrier for string-wrapped parcels, shopping bags, cord handles, cans with wire looped handles, pails with wire bails and other articles provided with strings or 75 parts which can be supported by the member 5.

It is thought from the foregoing description that the advantages and novel features of the invention will be readily apparent.

It is to be understood that changes may be 80 made in the construction and in the combination and arrangement of the several parts, provided that such changes fall within the scope of the appended claim.

What is claimed is:—
85
In combination with a handle having a groove therein opening out through the lower part of the handle, a pivot pin passing through the handle and through the inner end of the groove, a carrying member formed of a single piece of 90 spring wire and bent upon itself to form a pair of shanks with an eye at the junction of the shanks, said eye receiving a portion of the pivot pin, the lower end of one shank being curved to provide a curved hook having its extremity rolled 95 inwardly, the other shank having its lower end bent outwardly and downwardly with the extremity rolled inwardly, the two rolled parts normally contacting each other, the resiliency of the wire permitting the contacting parts to be separated 100 to permit a cord or the like to be passed into the hook or removed therefrom, and each shank having a thin part for increasing the resiliency at said thin part.
